MEANS FOR SIZING AND SURFACE FINISHING PAPER TUBES AND THE LIKE

Charles K. Dunlap, Hartsville, S. C., assignor to Sonoco Products Company, a corporation of South Carolina

Application March 21, 1950, Serial No. 151,013

12 Claims. (Cl. 93—83)

1

This invention relates to a method and means for sizing and surface finishing paper tubes and the like, and more particularly to such a method and means by which paper tubes or the like that have been treated with a thermo-active resinous material may be dimensionally sized and conditioned with a hard, slick, protective coating on their exterior surface.

The present invention is especially well adapted for use in forming textile yarn carriers, and for convenience is described and illustrated below principally in terms of its application for this purpose, although it is equally well adapted for use in any other instance where dimensional sizing and surface finishing of paper tubes or tubular bodies is desired.

Briefly described, the method of the present invention comprises treating a paper tube or the like with a thermo-active resinous material, holding the treated paper tube against rotation while moving it longitudinally through the bore of a rotating sizing die, and then transferring the paper tube directly to the bore of a heated curing die and allowing it to remain in this curing die for a period sufficient to effect setting of the resinous treating material in the surface layers of the paper tube.

The apparatus provided according to the present invention for carrying out this method comprises essentially a reciprocating mandrel adapted for carrying the treated paper tube; a first positioned stationary work-holding die coaxially aligned with this mandrel and having an internal diameter proportioned for gripping the paper tube against rotation but allowing longitudinal movement thereof; a second positioned rotating sizing die having an internal diameter proportioned for dimensionally sizing the paper tube; and a third positioned stationary curing die incorporating heating means for maintaining it at a desired curing temperature.

With the apparatus arranged in this manner, the dimensional sizing and surface finishing of the paper tube is accomplished with exceptional effectiveness by the rotating sizing die which irons the paper tube readily to the desired dimensional size and at the same time causes the resinous treating material to flow on the exterior surface of the paper tube so that a very slick protective coating is developed. Considerable heat is generated during this action of the sizing die, and the curing die is accordingly arranged to receive the paper tube directly from the sizing die so as to prevent blistering of the sized tube surface. The curing die is arranged for this purpose with a bore having a length

5 coextensive with the length of the paper tube being handled so that the sized tube surface is entirely confined until any excessive heat has been dissipated and a desired curing temperature has been established for setting the resinous treating material.

The present invention is described further below in connection with the accompanying drawings, in which:

10 Fig. 1 is an elevation, partly in section, of a textile yarn carrier such as might be formed from paper tubing treated in accordance with the present invention;

15 Fig. 2 is a similar elevation illustrating the paper tubing after dimensional sizing and surface finishing according to the present invention;

Fig. 3 is a sectional detail taken substantially on the line 3—3 in Fig. 1;

20 Fig. 4 is a plan view, partly diagrammatic, of a sizing and surface finishing apparatus embodying the present invention;

Fig. 5 is an enlarged sectional detail further illustrating the arrangement of the sizing and surface finishing head; and

25 Fig. 6 is a similar sectional detail illustrating a modified arrangement of the sizing and surface finishing head.

Referring now in detail to the drawings, the textile yarn carrier shown in Fig. 1 as an illustration of an article that might be formed from the paper tubing treated in accordance with the present invention, comprises a conventional form of textile bobbin having a tubular paper body or barrel 10, one end of which is turned in to form a rounded tip portion or nose at 12, as is common practice, and which turned-in end may be formed with a terminal flange as at 14 to provide a seat for an identification disk.

A textile yarn carrier as shown in Fig. 1 may be formed in accordance with the present invention from sized and surface finished paper tubing such as is illustrated in Fig. 2. In Fig. 2, this paper tubing is indicated generally by the reference character T, and as shown comprises a wound laminated tubular paper body 16 having its exterior surface conditioned with a protective coating as at 18. A wound laminated paper body 16, such as is illustrated in Fig. 2, may be formed by winding a paper blank convolutely upon itself to provide a laminated paper structure held

45 together by adhesives applied to the paper blank before winding, although it might be formed in other ways, too, such as by spiral winding, or a molded paper or fiber body might be used if desired. Also, the paper body 16 may be made up from any suitable paper or fiber stock. In the

case of textile yarn carriers, kraft stock is usually employed.

As previously mentioned, the protective coating 18 is developed on the exterior surface of the tubular paper body 16 after it has been treated with a suitable thermo-active resinous material, such as a Bakelite type resin. This resin treatment may be carried out effectively either by mixing the resin with the adhesive applied to the blanks before winding, if a wound laminated type of structure is to be used, or by dipping the fully formed tubular paper body 16 in the resin.

The apparatus for dimensionally sizing and surface finishing the paper tubing T to develop this protective coating 18 on the tubular paper body 16 after the resin treatment, is illustrated in Figs. 4 and 5 of the drawing. As shown in Fig. 4, this apparatus comprises a suitable frame structure or supporting base 100 on which the previously mentioned reciprocating mandrel is disposed as at 102, the stationary work-holding die at 104, the rotating sizing die at 106, and the stationary curing die at 108.

The reciprocating mandrel 102 is mounted to extend from a crosshead 110 which is arranged for sliding movement on guide rods 112 carried on the frame structure 100 by suitable support brackets as at 114 and 116. The crosshead 110 is moved on the guide rods 112 to reciprocate the mandrel 102 by means of an hydraulic actuating system comprising a pressure cylinder 118 from which a piston rod 120 extends to the crosshead 110. The crosshead 110 is formed with a laterally extending arm portion 122 disposed for contact with adjustable limit stops 124 and 126 to regulate the reciprocating stroke of the mandrel 102, the limit stops 124 and 126 being carried on an operating bar 128 arranged to actuate a conventional spring-loaded reversing mechanism 130 provided for automatically operating a control valve 132 through which the hydraulic actuating system is controlled to obtain the desired reciprocating motion of the crosshead 110 and the mandrel 102. Pressure lines 134, 136, 138 and 140 and a reservoir 142 are arranged in the usual manner to complete this hydraulic system.

The arrangement of the sizing and surface finishing head, comprising the work-holding die 104, the rotating sizing die 106, and the curing die 108, is shown more in detail in Fig. 5 of the drawing. The stationary work-holding die 104, which is positioned first in relation to the working stroke of the mandrel 102, is mounted as at 144 on a support bracket 146 carried on the frame structure 100. As previously mentioned, the bore 148 of this work-holding die 104 is proportioned for gripping the paper tubing T against rotation while allowing it to be moved longitudinally by the mandrel 102.

The rotating sizing die 106 is disposed immediately beyond the work-holding die 104, and is mounted in this position as at 150 on a tubular member 152 arranged concentrically over the work-holding die 104 for rotation in double-thrust bearings 154 and 156, which are mounted, respectively, in the work-holding die supporting bracket 146, and a bracket plate 158 adjustably positioned on the guide rods 112 by means of opposed nuts as at 160 to tighten the bearings 154 and 156 properly in relation to a spacing sleeve 162 carried on the tubular member 152. This spacing sleeve 162 also supports a sprocket wheel 164 which, together with the spacing sleeve 162, is secured to the tubular member 152 as by a set screw at 166, and which is adapted to be

driven by a sprocket chain drive 168 from an electric motor or the like 170 (compare Fig. 4) for rotating the sizing die 106. The bore 172 of the rotating sizing die 106 is proportioned in accordance with the desired finished size for the tubing T.

The curing die 108 is in turn disposed immediately beyond the rotating sizing die 106, being mounted in this position as at 174 on the previously mentioned support bracket 116, which also supports the guide rods 112 at one end. Like the work-holding die 104, the bore 176 of the curing die 108 is proportioned for gripping the paper tubing T against rotation, and is formed in a length coextensive with the length of the paper tubing T being handled. This curing die 108 also incorporates heating means, preferably electrical means as indicated in Figs. 4 and 5 at 178, for maintaining it at a desired curing temperature.

In operation, the dimensional sizing and surface finishing of the paper tubing T is carried out with the apparatus illustrated in Figs. 4 and 5 by placing a length of the paper tubing T, after treating with a resinous material as noted above, on the mandrel 102 at the beginning of its forward or working stroke. The mandrel 102, is, of course, proportioned in accordance with the length of the paper tubing T to be handled, and it will be noted that the mandrel 102 is shoudered, as at 180, to provide a seat for the paper tubing T as the mandrel 102 forces it longitudinally through the sizing and surface finishing head.

As the mandrel 102 with a length of paper tubing T in place is moved forward on its working stroke, the leading end of the paper tubing T enters and moves longitudinally through the first positioned work-holding die 104 which, as previously mentioned, is proportioned to allow this longitudinal movement but which grips the paper tubing T against rotation so that as it is moved forward by the mandrel 102 to reach the rotating sizing die 106, it is held securely from rotation while the sizing and surface finishing is effected by the action of this die 106. The action of the rotating sizing die 106 consists essentially of an ironing effect which lays the surface of the paper tubing T smooth and reduces it to the desired size, and which effect is accompanied by the generation of considerable heat which causes the resinous material contained in the paper tubing T to flow and form a smooth, slick, protective coating on the exterior surface of the paper tubing T in a particularly effective manner.

As the mandrel 102 moves further to carry the paper tubing T progressively through the rotating sizing die 106, the paper tubing T is received immediately in the bore 176 of the curing die 108, so that it remains confined until the heat generated by the sizing operation is dissipated so as to avoid any tendency of the exterior surface of the paper tubing T to blister as a result of this heating. Also, as the bore 176 of the curing die 108 is proportioned as in the work-holding die 104 for gripping the paper tubing T against rotation, the trailing end of the length of paper tubing T being handled will be properly held in the rotating sizing die 106 even after it passes beyond the work-holding die 104.

The entrance edge of the bore 176 of the curing die 108 is relieved as at 182 to allow the paper tubing T to be received readily from the sizing die 106, while the bore 172 of the sizing die 106 is formed to open in the rear face of the sizing

die 106 with a square edge as at 184, and thereby form an abutment for stripping the paper tubing T from the mandrel 102 after it has been moved into the curing die 108 and the mandrel 102 starts to withdraw for its return stroke. The paper tubing T is thus left in the curing die 108 until a succeeding length of paper tubing T has been placed on the mandrel 102 for a new cycle of operation and this succeeding length of paper tubing T has been moved through the sizing and surface finishing head by the mandrel 102 to displace the first length of paper tubing T from the curing die 108. By adjusting the cycle of operation, and regulating the heating means 178 at the curing die 108, a proper curing period may be allowed for setting the resinous material in the outer layers of the paper tubing T, so that each length of the tubing T emerges from the curing die not only dimensionally sized but also with a hard, slick, protectively coated exterior surface which has excellent physical properties.

The apparatus described above for carrying out this sizing and surface finishing operation may be arranged alternatively, if desired, with a plurality of rotating sizing dies mounted coaxially in succession between the work-holding die 104 and the curing die 108, rather than with just the single sizing die 106. When this is done the sizing dies should each be rotated in a direction opposite to an adjacent sizing die, and the bores of the sizing dies should decrease successively in diameter. With the apparatus arranged in this manner, the sizing action can be effected both more gradually and to a greater extent, and this, as well as the successively opposite directions of rotation of the sizing dies, makes it much easier to handle tubular bodies which are difficult to grip against rotation during sizing.

I claim:

1. A machine for dimensionally sizing and developing a hard, slick, protective coating on the exterior surface of a resin coated tubular paper body, said machine comprising at least one sizing die mounted for rotation, a stationary curing die mounted in coaxial alignment with said sizing die, means for moving said resin coated tubular paper body through said sizing die and into said curing die, means for rotating said sizing die, and means for maintaining said curing die at a desired curing temperature.

2. A machine for dimensionally sizing and developing a hard, slick, protective coating on the exterior surface of a resin coated tubular paper body, said machine comprising, in combination, a first positioned stationary work-holding die proportioned in diameter for gripping said resin coated tubular paper body against rotation while allowing longitudinal movement thereof, a second positioned sizing die mounted for rotation coaxially with respect to said work-holding die, a third positioned stationary curing die disposed in coaxial alignment with said sizing die, means for moving said resin coated tubular body longitudinally through said work-holding die and said sizing die and into said curing die in succession, drive means for rotating sizing die, and heating means for maintaining said curing die at a desired curing temperature.

3. A machine for dimensionally sizing and developing a hard, slick, protective coating on the exterior surface of a resin coated tubular paper body, said machine comprising a stationary work-holding die, at least one rotatable sizing

die, and a stationary curing die coaxially disposed with respect to each other and mounted in succession for forming a substantially continuous cylindrical passageway through which said resin coated tubular paper body may be moved longitudinally, and a reciprocable mandrel for moving said resin coated tubular paper body longitudinally through said dies, said work-holding die and said curing die being proportioned in diameter for gripping said resin coated tubular paper body against rotation but allowing longitudinal movement thereof for dimensional sizing and surface development by said rotatable sizing die.

15 4. A machine as defined in claim 3 and further characterized in that a plurality of rotating sizing dies are mounted coaxially in succession between said work-holding die and said curing die, said sizing dies each being rotated in a direction opposite to an adjacent sizing die, and the bores of said sizing dies successively decreasing in diameter.

25 5. A machine for dimensionally sizing and surface finishing a paper tube that has been treated with a thermo-active resinous material, said machine comprising, in combination, a work-supporting mandrel mounted for reciprocation and adapted for carrying said treated paper tube, and, coaxially aligned within the stroke of said mandrel, a stationary work-holding die proportioned in diameter for gripping said treated paper tube but allowing longitudinal movement thereof, a rotatable sizing die, and a stationary curing die, means for reciprocating said mandrel, 30 means for rotating said sizing die, and means for maintaining said curing die at a desired curing temperature.

35 6. A machine for dimensionally sizing and surface finishing laminated paper tubes that have been treated with a thermo-active resinous material, said machine comprising, in combination, a stationary work-holding die having an internal diameter adapted for gripping said treated paper tubes against rotation but allowing longitudinal movement of said tubes therethrough, a rotatable sizing die disposed coaxially with respect to said work-holding die for receiving therefrom treated paper tubes moved longitudinally therethrough, and a stationary curing die disposed coaxially 40 with respect to said sizing die for receiving therefrom said treated paper tubes after sizing, said curing die also having an internal diameter adapted for gripping said treated paper tubes against rotation but allowing longitudinal movement thereof, means for moving said treated paper tubes longitudinally through said work-holding and sizing dies and into said curing die, means for rotating said sizing die, and heating means for maintaining said curing die at a desired curing temperature.

45 7. A machine for dimensionally sizing and surface finishing a paper tube that has been invested with a surface coating of a thermo-active resin, said machine comprising a first positioned work-holding die, said work-holding die having an internal diameter adapted for gripping said treated paper tube but allowing longitudinal movement thereof, a second positioned rotating sizing die coaxially disposed with respect to said work-holding die, a third positioned stationary curing die 50 coaxially disposed with respect to said sizing die, said curing die also having an internal diameter adapted for gripping said treated paper tube against rotation but allowing longitudinal movement thereof, and having a length coextensive

with said treated paper tube whereby it is adapted for preventing blistering of the tube surface following sizing, means for moving said treated paper tube longitudinally through said dies in succession, and heating means for maintaining said curing die at a desired curing temperature.

8. In a machine for dimensionally sizing and surface finishing a paper tube that has been treated with a thermo-active resinous material wherein the treated paper tube is supported on a reciprocating mandrel and is moved by said mandrel longitudinally through a rotating sizing die to smooth the surface and size the tube to the desired outside diameter, the improved means for dimensionally sizing and surface finishing the treated paper tube which comprises a first positioned stationary work-holding die having an internal diameter adapted for preventing rotation of an unsized paper tube being moved longitudinally therethrough, said die being supported in coaxial alignment with said reciprocating mandrel, a second positioned rotating sizing die disposed coaxially with respect to said work-holding die, and a third positioned curing die disposed coaxially with respect to said sizing die and incorporating heating means for maintaining it at a desired curing temperature.

9. A machine for dimensionally sizing and surface finishing a paper tube that has been treated with a thermo-active resinous material, said machine comprising a reciprocating mandrel adapted for carrying said treated paper tube, a first positioned stationary work-holding die coaxially aligned with said mandrel and having an internal diameter proportioned for gripping said treated paper tube against rotation but allowing longitudinal movement thereof, a second positioned rotating sizing die, a third positioned stationary curing die incorporating heating means, said sizing die and said curing die both being likewise coaxially aligned with said mandrel, and means for reciprocating said mandrel for moving said treated paper tube through said work-holding and sizing dies and into said curing die.

10. A machine for dimensionally sizing and surface finishing a paper tube that has been treated with a thermo-active resinous material, said machine comprising a mandrel mounted for reciprocation and adapted for carrying said treated paper tube, a stationary work-holding die, a rotating sizing die, and a stationary curing die coaxially disposed with respect to said mandrel and mounted in succession for forming a substantially continuous bore through which said treated paper tube may be moved longitudinally by said mandrel, and means for reciprocating said mandrel for moving a treated paper tube longitudinally through said work-holding and sizing dies and into said curing die, the bore of said sizing die being formed to open in the rear face of said die with a square edge, and the entrance edge of the bore of said curing die being relieved whereby the rear face of said sizing die forms an abutment for stripping said treated paper tube from said reciprocating mandrel after the tube has been moved into said curing die by the mandrel.

11. A machine for dimensionally sizing and surface finishing a paper tube that has been treated with a thermo-active resinous material, said machine comprising a frame structure, slide bars mounted on said frame structure, a cross-head disposed for reciprocation on said slide bars, a mandrel supported on said crosshead and adapted for carrying said treated paper tube, a stationary work-holding die, a rotating sizing die, and a stationary curing die, all of said dies being mounted on said frame structure coaxially in relation to said mandrel and being disposed in succession for forming a substantially continuous cylindrical passage-way through which said treated paper tube may be moved longitudinally by said mandrel, means carried by said frame structure for reciprocating said mandrel and thereby move said treated paper tube longitudinally through said work-holding and sizing dies and into said curing die, means for rotating said sizing die, and means for maintaining said curing die at a desired curing temperature, said work-holding and sizing dies both having a bore shorter than the length of said treated paper tube, the bore of said work-holding die having an internal diameter proportioned for gripping said treated paper tube against rotation during sizing by said rotating sizing die but allowing longitudinal movement of said treated paper tube, the bore of said sizing die being formed to open in the rear face of said die with a square edge, and the entrance edge of the bore of said curing die being relieved whereby the rear face of said sizing die forms an abutment for stripping said treated paper tube from said reciprocating mandrel after the tube has been moved into said curing die by the mandrel, and said curing die also having an internal bore diameter adapted for gripping said treated paper tube against rotation but allowing longitudinal movement thereof, and having a length coextensive with said treated paper tube whereby said curing die is adapted for preventing blistering of the tube surface following sizing.

12. A machine as defined in claim 11 and further characterized in that a tubular member is mounted for rotation on said frame structure in spaced relation concentrically over said work-holding die, and said sizing die is mounted at the rear end of said tubular member and thereby disposed for rotation adjacent the rear face of said work-holding die.
